UNITED STATES PATENT OFFICE.

JOHN H. CURLEY, OF BROCKTON, MASSACHUSETTS.

DESIGN FOR A HOOF-PAD.

43,738.

Specification for Design.

Patented Mar. 25, 1913.

Application filed December 19, 1911. Serial No. 666,847. Term of patent 14 years.

To all whom it may concern:

Be it known that I, JOHN H. CURLEY, a citizen of the United States, residing at Brockton, in the county of Plymouth and State of Massachusetts, have invented a new, original, and ornamental Design for Hoof-Pads, of which the following is a specification, reference being had to the accompanying drawing, forming part thereof,

in which the figure is a perspective view of a hoof-pad, showing my new design.

I claim:

The ornamental design for a hoof pad as shown.

JOHN H. CURLEY.

Witnesses:

W. P. ABELL,
P. W. PEZZETTI.
